UNITED STATES PATENT OFFICE.

EDWIN REUEL MERRILL, OF COLUMBUS, OHIO, ASSIGNOR TO JOSEPH A. JEFFREY, OF COLUMBUS, OHIO.

MINING-MACHINE.

No. 798,201.

Specification of Letters Patent.

Patented Aug. 29, 1905.

Application filed April 7, 1898. Serial No. 676,812.

To all whom it may concern:

Be it known that I, EDWIN REUEL MERRILL, a citizen of the United States, residing at Columbus, in the county of Franklin and State of Ohio, have invented certain new and useful Improvements in Mining-Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a side elevation of a mining-machine embodying my improvements. Fig. 2 is a longitudinal section. Fig. 3 is a top plan view. Fig. 4 is a transverse section on the line xx of Fig. 2. Fig. 5 is a longitudinal vertical section through the motor and gearing. Figs. 6 to 13 are detail views.

The machine is composed of two main parts, one being a bed-frame and the other a sliding carriage. The bed-frame has the longitudinal side bars A A, which at intervals are joined to cross-braces or frame-pieces a , each having a ground cross-bar a' and legs or uprights a'' , which are secured to the side bars A. The side bars have a vertical portion a^3 and a horizontal flange a^4 . At the rear end there is a cross-bar a^5 , which not only serves to firmly brace together the rear ends of the side bars A, but also provides means for moving the machine laterally or otherwise on the ground, it having extensions a^6 , against which the operatives can place bars or levers. At the front end the side bars A are joined by a cross-bar B, which is also utilized to support the forward portion of the sliding carriage, it having a guide at b , furnished by downward-extending arms or hangers b' . The front end of the machine is also provided with a jack or fastening device C, having the legs $c c$ hinged to the bed-bar, the sleeve c' on the legs, the jack-point c'' , carried by a threaded stem c^3 , the threaded sleeve c^4 , and the hand-wheel c^5 , secured to sleeve c^4 .

The carriage or sliding portion of the entire machine consists principally of two frames, one a cutter-supporting frame (indicated as a whole by D) and the other a platform or frame at the rear, (indicated as a whole by E.) The frame or platform E is fitted to move between the side bars A of the bed. It may be formed of a supporting-plate

and the several necessary attachments where- 55 by it can have secured to it a motor or engine and the shafting and gearing necessary to actuate the cutters and to move the carriage longitudinally of the bed, or the metallic parts constituting this rear frame or plat- 60 form can be all or approximately all cast integral and shaped so as to serve not only as a general support for the aforesaid parts, but also so as to serve as the field metal of a motor. The latter plan of construction is illus- 65 trated in the drawings. F indicates the metallic part of a motor constituting a magnetic circuit of its field, and at the bottom there are arms or extensions, as at $f f'$, projecting in suitable directions for providing a support. 70 At the front edge of this frame or platform and preferably below it there are a guide for the rear end of the cutter-frame and means for adjusting said frame longitudinally and for fastening it and which will be described. 75

By inspecting the drawings it will be seen that provision is made for a motor having a vertical armature.

The armature-shaft is indicated by G, the lower end passing through a bearing at f^2 in 80 the bottom wall f^3 of the casting for the platform or for the bottom of the motor. The commutator is situated at f^4 . The armature-shaft at its upper end has a bearing at f^5 in a cross-piece or closing-plate f^6 , secured to the 85 motor metal and lying across the upper end of the armature-chamber.

H is the armature-pinion. It drives a larger gear-wheel I, which is arranged horizontally and preferably directly behind the armature-shaft. This wheel I is secured to a vertical shaft J, the latter also carrying at its lower end a sprocket K, which engages with and drives the cutters. Shaft J is mounted in vertical bearings at j and j' , carried by a bracket 90 or brackets cast with or bolted to the motor or frame casting. This shaft has also secured to it a worm L and a pinion L.

M is a cross-shaft mounted on the rear part of the carriage, preferably in bearings at m , 100 provided by brackets or arms m' , cast with or secured to the rear frame or motor metal. This shaft M has carriage-moving pinions N N, which lie above and engage with racks $n n$, that are rigidly secured to the side bars A of 105 the bed. These are preferably lantern-racks in which the teeth are separated by apertures or passages extending vertically entirely

through the bars, so that slack, cuttings, or other foreign particles can escape or be crowded downward, and thus prevent choking, binding, or clogging of the racks and the wheels

- 5 N. In order to prevent upward displacement, use is made of bracing devices, preferably antifriction-rollers O, mounted in extensions m^2 of the brackets m' , these rollers lying under the horizontal flange parts a^4 of the side bars A. 10 Shaft M is provided with a loose worm-wheel P, engaging with the worm L and constantly rotated thereby. The size of this wheel P, its number of teeth, and the pitch of the worm L are so related that a relatively 15 high speed shall be communicated to the shaft M and the pinions N when the carriage is being drawn backward on the bed. The pinion l engages with a larger wheel Q, which is on the upper end of a vertical shaft q and which 20 is mounted in bearings at $q' q^2$, carried by the brackets above described, secured to or formed with the rear frame or the motor metal. This shaft q also carries a worm R, which engages 25 with a worm-wheel S, mounted loosely on the shaft M.

T is a clutch splined to the shaft M and situated between the loose wheels P and S. It can be moved to engage with one worm-wheel or the other or can be situated in an 30 inactive position. When the wheel S is clutched to the shaft M, a relatively slow rotation will be imparted to the shaft M and the pinions N, because of the speed-reducing gear at l Q and the relations of the worm R and 35 its pitch to the diameter and teeth of the wheel S. The clutch T is provided with a series of grooves or ribs t, and with these engage a ribbed or grooved plate U, carried by a lever V, which is pivoted at v and extends 40 to a point behind the gearing and has its rear end curved or cam-shaped, as shown at v'. W is a cam adapted to be adjustably secured to the bed-frame bar a^5 . With the clutch-throwing devices a hand-lever V² may be 45 combined, adapted to operate in any suitable way. When the clutch T is in engagement with the wheel S, the carriage will be advanced forward slowly—that is, with a speed corresponding to the rapidity of the cut in 50 the coal. When it reaches the forward end of its path at the completion of the cut, the clutch T is moved away from wheel S and into engagement with the wheel P. The latter is rotating in a direction opposite to 55 that of the wheel S and with a higher speed, and therefore when the clutch engages with it the carriage is brought back more rapidly, and the backward movement continues until the cam v' on lever V strikes the cam W, 60 whereupon the clutch is moved away from wheel P to its inactive position and the carriage stops, although the motor may continue in motion. The wheels P and S are revolving continuously and, as above said, oppositely. 65

By arranging the gearing in the manner described I am enabled to bring the framework low and to place the entire mechanism compactly in a reduced space.

Passing now to the cutter-frame D, it will 70 be seen to be composed of a cross - head 1 and a central longitudinal carrier 2. Preferably, these are supplemented by guides 3, extending back from the cutter-head and converging rearward toward the central carrier 75

2. The carrier 2 is practically a unitary part, though I construct it of two side bars 4 4 and an intermediate brace, preferably formed of a channel-bar 5, the flanges of which are secured to the side bars 4 4. At the rear end 80 this carrier is secured to a guide and fastening-piece 6, which has vertical flanges 7, and a cross-plate 8, provided with an aperture 9.

The above - described platform or frame-casting F has a guideway at 18, formed by a 85 slot or groove into which the bars 4 5 6 can be fitted and which permits it to be moved forward and back therein.

10 is a nut passing upward through the aperture 9. 90

11 is a screw engaging with the threaded aperture in the nut 10, this screw being supported at its inner end at a seat at 12 and at its outer end in a bearing at 13. In addition to the screw for fastening the nut 10 there is 95 a clamping device having a nut 14 and a washer 15 cast together.

When it is desired to adjust the cutter-frame forward or back on the platform or rear frame, the clamp at 14 15 is loosened and the screw 100 11 is turned in the proper direction, and the draft thereby exerted causes the nut 10 to pull or push the carrier 2 and the parts connected therewith forward or back.

16 represents the chain, having the cutters 105 17 attached thereto. This chain engages with and is driven by the sprocket-wheel K and passes thence along the guides 3 and around the front cross-head 1. It is this chain which requires adjustment, either tightening or loosening, from time to time and for which operation the screw 11 and nut 10 are provided. 110

What I claim is—

1. In a mining-machine the combination of a bed, a carriage movable thereon, cutters on 115 said carriage, a motor on said carriage having a vertical shaft, a horizontal feed-shaft geared with said bed to actuate the carriage, two gearing members loose on said horizontal feed-shaft, means for connecting either of said members with the feed-shaft, two vertical shafts 120 on different axes and geared together and differently-speeded gearings connecting the motor-shaft with said loose gearing members respectively to turn them in opposite directions, and means for connecting the motor-shaft with the cutters to actuate the latter. 125

2. In a mining-machine, the combination of a bed, a carriage movable thereon, cutters on 130 said carriage, a motor on said carriage having

a vertical shaft, a horizontal feed-shaft geared with said bed to actuate the carriage, two gearing members loose on said horizontal feed-shaft, means for connecting either of said members with the feed-shaft, two vertical shafts on different axes and differently-speeded gearings connecting the motor-shaft with said loose gearing members respectively to turn them in opposite directions, and means for connecting one of said vertical shafts with the cutters to actuate the latter.

3. In a mining-machine, the combination of a bed, a carriage movable thereon, cutters on said carriage, a motor on said carriage having a vertical shaft, a horizontal feed-shaft geared directly with said bed to actuate the carriage, two gearing members loose on said horizontal feed-shaft, means for connecting either of said members with the feed-shaft, two vertical shafts on different axes, the first geared directly with the motor-shaft and said two shafts having intermeshing gears Z , Q , differently-speeded gearings connecting said vertical shafts respectively with said loose gearing members to turn the latter in opposite directions, and means for connecting one of said vertical shafts with the cutters to actuate the latter.

4. In a mining-machine the combination of a bed, a carriage movable thereon, cutters on said carriage, a motor on said carriage having a vertical shaft, a horizontal feed-shaft geared directly with said bed to actuate the carriage, two gearing members loose on said horizontal feed-shaft, means for connecting either of said members with the feed-shaft, two vertical shafts and differently-speeded gearings connecting the two vertical shafts with said loose gearing members respectively to turn them in opposite directions and means for connecting the motor-shaft with the cutters to actuate the latter.

5. In a mining-machine the combination of a bed, a carriage movable thereon, cutters on said carriage, a motor on said carriage having a vertical shaft, a horizontal feed-shaft geared directly with said bed to actuate the carriage, two worm-wheels loose on said horizontal feed-shaft, means for connecting either of said worm-wheels with the feed-shaft, two vertical shafts and differently-speeded gearings connecting the vertical shafts with said worm-wheels respectively to turn them in opposite directions, and means for connecting the motor-shaft with the cutters to actuate the latter.

6. In a mining-machine the combination of a bed, a carriage movable thereon, cutters on said carriage, a motor on said carriage having a vertical shaft, a horizontal feed-shaft geared with said bed to actuate the carriage, two gearing members loose on said horizontal feed-shaft, means for connecting either of said members with the feed-shaft, a central vertical cutter and carriage-actuating shaft geared

with the motor-shaft for relatively high speed, a second carriage-actuating vertical shaft mounted eccentrically to the first-mentioned vertical shaft and geared with the latter, and differently-speeded gearings, connecting said two vertical shafts respectively with said loose gearing members on the horizontal feed-shaft to turn them in opposite directions, and means for connecting the first-mentioned vertical shaft with the cutters to actuate the latter.

7. In a mining-machine the combination of a bed, a carriage movable thereon, cutters on said carriage, a motor on said carriage having a vertical shaft, a horizontal feed-shaft geared with said bed to actuate the carriage, a central vertical cutter and carriage-actuating shaft geared with the motor-shaft for relatively high speed, a second vertical carriage-actuating shaft mounted on a different axis from the first shaft and connected therewith by slowing-down gearing, a worm on the first vertical shaft, a loose worm-wheel on the feed-shaft, connected directly with said worm, a worm on the second vertical shaft, a second loose worm-wheel on the feed-shaft engaging with the last-said worm, a clutch between said loose worm-wheels on the feed-shaft and means for connecting the central vertical shaft with the cutters, substantially as set forth.

8. In a mining-machine, the combination of the bed, the carriage having the cutter-frame and the frame or platform at the rear, the motor carried by said rear frame and having a vertical armature-shaft, the two vertical shafts in rear of the motor, said shafts being eccentric to each other, the gearing at the lower end of one of said shafts connecting it with the armature-shaft, the gearing at the upper ends of said shafts connecting them together, the horizontal transverse carriage-moving shaft, and the two trains of differently-speeded continuously-rotating gearing respectively connected with the said vertical shafts and both detachably connected with the carriage-moving shaft, substantially as set forth.

9. In a mining-machine, the combination of the bed, the carriage having a cutter-frame and a frame or platform at the rear, the electric motor on the said rear frame and having a vertical armature-shaft, a vertical shaft in rear of the armature, gearing connecting it to the armature-shaft, a chain-wheel at the lower end of said rear vertical shaft, a transverse carriage-moving shaft, bed-racks near the level of said transverse shaft, worm-gearing connecting said transverse shaft directly to the said rear vertical shaft, pinions on said transverse shaft in line with and engaging directly with the racks, said worm-gearing being adapted to rotate the transverse shaft in one direction for moving the carriage, oppositely-rotating devices comprising a second vertical shaft, worm and worm-wheel for rotating the trans-

- verse shaft in the opposite direction with a different speed, and means for connecting said transverse shaft to either of said sets of gearing, substantially as set forth.
- 5 10. In a mining-machine, the combination of the bed, the carriage, having the cutter-frame, and the frame or platform at the rear, the electric motor on the rear frame having a vertical armature-shaft, a vertical shaft behind the 10 motor, a second vertical shaft behind the motor, and eccentric to the first-mentioned vertical shaft, a transverse shaft engaging directly with the bed for moving the carriage, a worm-wheel on the transverse shaft, a worm 15 on the second vertical shaft, gearing connecting the second vertical shaft with the motor-shaft, said worm and worm-gear being adapted to move the carriage in one direction at a predetermined speed, means for moving the carriage 20 in the opposite direction at a different speed, and means for throwing into operation either of the sets of carriage-moving devices substantially as set forth.
11. In a mining-machine, the combination of 25 the bed, the carriage having the cutter-frame and the frame or platform at the rear, the electric motor on said rear frame, a vertical shaft in the rear of said motor geared directly to the armature, a transverse shaft, for moving 30 the carriage, geared directly to the vertical shaft, a second vertical shaft eccentric to and geared directly to the first vertical shaft and geared directly to the transverse shaft, the two 35 gearings for the transverse shaft being adapted to rotate it in opposite directions with different speeds, means for throwing into operation either of said sets of gearing and a cutter-driving wheel carried by one of the vertical shafts, substantially as set forth.
- 40 12. In a mining-machine, the combination of the bed, the carriage having the cutter-frame and the rear platform or frame, the motor on the rear frame having a vertical armature-shaft, the vertical shaft in rear of the motor 45 geared directly to the armature-shaft, the horizontal chain sprocket-wheel on said vertical shaft, the transverse shaft, for moving the carriage, geared directly to the vertical shaft, the feed-pinion on the transverse shaft, and 50 the rack on the bed below the pinion and having openings between its teeth, substantially as set forth, the rack being engaged directly by the feed-pinion on the transverse shaft.
13. In a mining-machine, the combination of the bed, a carriage having a cutter-frame and a rear frame or platform, an electric motor on the said rear frame having a vertical armature-shaft, a vertical shaft in the rear of the motor and geared directly to the armature-shaft, said vertical shaft having a relatively large gear-wheel, a sprocket-wheel, a worm and a relatively small gear wheel or pinion, a transverse carriage-moving shaft geared directly to the said worm and directly to the carriage for moving the carriage rapidly in one direction a train of gear interposed between said pinion and said transverse shaft for moving the carriage slowly in the opposite direction and the clutches interposed between said trains of gearing and said transverse shaft. 55
14. In a mining-machine, the combination of a bed, a carriage movable thereon, cutters on said carriage, a motor on said carriage, two vertical shafts, one of which is geared to the motor-shaft and both of which are geared together, a transverse carriage-moving shaft geared with said bed to actuate the carriage, trains of differently-speeded gearing interposed respectively between each of said vertical shafts and the said transverse shaft, and 60 adapted to turn the said feed-shaft in opposite directions, the clutches interposed between said transverse shaft and each of said trains of gearing and means for connecting one of said vertical shafts with the cutters to actuate 65 the latter, substantially as set forth.
15. In a mining-machine the combination of a bed, a carriage movable thereon, cutters on said carriage, a motor on said carriage, a horizontal feed-shaft geared with said bed to actuate the carriage, two vertical shafts geared to the said motor and each directly geared to said feed-shaft and adapted to turn it in opposite directions and at different speeds, the clutches interposed between said feed-shaft 70 and the sets of gearing arranged to actuate it and means for connecting one of said vertical shafts with the cutters to actuate the latter, substantially as set forth. 75
